UNITED STATES PATENT OFFICE.

JAMES WALKER, OF ELIZABETH, NEW JERSEY.

TUBE EXPANDER AND FLARER.

Application filed December 26, 1925. Serial No. 77,785.

This invention relates to improvements in tube expanding and flaring tools, and has for one of its objects to provide a tool of simple and practical construction which will effectively operate to expand a tube and flare the end thereof.

Another object is to provide novel means for retaining the flaring elements in operative position in the tool so that the same may be contacted by a mandrel utilized to rotate said tool while in a tube and be forced by such contact to engage and flare the end of said tube.

The above and other objects will appear more clearly from the following detailed description, when taken in connection with the accompanying drawings, which illustrate preferred embodiments of the inventive idea.

20 In the drawings—

Figure 1 is a longitudinal section through one form of tool showing the same in operative position in a tube;

Figure 2 is a plan view of the tool shown in Figure 1;

Figure 3 is an end elevation partly broken away and shown in section;

Figure 4 is a transverse section taken on the line 4—4 of Figure 1;

Figure 5 is a similar section taken on the line 5—5 of Figure 1;

Figure 6 is a longitudinal section through another form of tool;

Figure 7 is a plan view thereof;

Figure 8 is an end elevation;

Figure 9 is a transverse section on the line 9—9 of Figure 6; and

Figure 10 is a similar section on the line 10—10 of Figure 6.

40 The form of the invention shown in Figures 1 to 5 is best adapted for lighter work such as the expansion of small boiler tubes 11 and the like in the head 12. The body portion 13 of the tool is of substantially cylindrical formation and of a diameter less than that of the tube to be expanded, said body portion being provided with a longitudinal opening 14 therethrough for the reception of the usual tapered mandrel, indicated in dotted lines, which is employed to rotate the tool when expanding a tube. Formed in the body portion 13 in any preferred manner are a plurality of recesses 15 which extend laterally through said body portion so as to communicate with the longitudinal opening 14. The side walls of said

recesses are arcuate in formation, as shown in Figure 5, and are designed to receive the expanding rollers 16. When the tapered mandrel is inserted into the opening 14 the same will engage the rollers 16 and force the same laterally outward into engagement with the inner surface of the tube 11 and thus expand the same. The recesses 15 and consequently the rollers 16 are arranged diagonally with respect to the longitudinal axis of the body portion, a feature well known in the art, and this arrangement assists in feeding the rollers into the tube and the mandrel into the opening 14.

70 The flaring means of the tool consists of a plurality of spherical members 17 mounted in the outer ends of the recesses 15, there being one of these members associated with each of the rollers 16 and being directly aligned therewith. The diameters of the spherical members are slightly greater than that of the rollers 16 and in order to enable each of said members 17 to properly engage the end of the tube 11 to flare the same the adjacent end of the associated roller 16 is recessed, as indicated at 18, to form a concavity capable of receiving a portion of the spherical member 17 so that, in effect, there is an overlapping relation between the two elements. The spherical members 17 are likewise capable of being contacted by the tapered mandrel and as the latter is fed into the tool and as said members engage the end of the tube, said mandrel will operate 80 to force the members outwardly and thus produce the annular flare 19 on said tube. It will be understood that as the mandrel is rotated a similar movement will be imparted to the rollers 16 and spherical members 17 thus reducing, to a large extent, the friction between the parts.

90 The outer end of the body portion 15 is enlarged to provide an annular flange 20 and said flange is recessed adjacent each of the members 17 to form an overlapping retaining flange 21 which will limit the lateral outward movement of the member 17 produced by the action of the mandrel. In order to further retain the spherical members in position against endwise movement there is mounted in the recess formed by the flange 20 a ring member 22 preferably secured to the flange 20 by cotter pins or the like 23 which are expanded through aligned openings formed in the flange and ring member, as clearly shown in Figure 3.

In the form of the invention shown in Figures 6 to 10 which is preferably used for heavier work, the body portion 24 is drilled from one end to provide a plurality of longitudinal recesses 25 in which the diagonally arranged rollers 26 are disposed, the outer ends of said recesses being thereafter closed by a cap 27, preferably welded to the end of the body portion. The recesses 25 are formed at their outer edges with overhanging lips 28 to limit the outward movement of the rollers 26, but the inner edges of said recesses are so formed that the rollers 26 will be free to move inwardly into the longitudinal opening 29 which extends throughout the body portion. Owing to this formation of the recesses the tool, in practice, is rested upon the end cap 27 in a vertical position before withdrawing the mandrel 30 from the tube after an expanding operation. Between the inner ends of adjacent recesses 25 the body portion 24 is formed with further recesses 30 for the reception of the spherical flaring members 31 so that the rollers 26 and members 31 will be alternately arranged about the circumference of the body portion. By this alternate arrangement, it is possible to cause each spherical member 31 to overlap a considerable portion of the adjacent ends of the rollers 26 and thereby permit the members 31 to properly engage the end of a tube in order to give the same the desired flare. The spherical members are free to move inwardly and outwardly in the recesses 30, but in order to limit the outward movement thereof the body portion 24 has mounted thereon a split collar 32, the sections of which are formed with grooves 33 for the reception of an annular flange 34 formed upon the body portion so as to prevent longitudinal movement of the collar on said body portion. The sections of said collar are retained in operative position by a ring member 35 which encircles the reduced end of the collar and which

snaps into retaining position over a ring 36 also encircling said collar. The inner enlarged end of the collar 32 is formed with an annular retaining flange 37 which overlaps the spherical members 31 and through this overlapping relation limits the outward movement thereof when acted upon by the mandrel.

What is claimed is:

1. A tube expanding and flaring tool, including a body having an opening therethrough for the reception of a tapered mandrel, rollers carried by said body and movable laterally, by contact of the tapered surface of said mandrel therewith, into engagement with a tube to be expanded, and spherical flaring members carried in said body at one end thereof and each having a single point of contact with the tapered surface of said mandrel and movable laterally outward relative thereto, as the mandrel is fed longitudinally through the opening in said body, to engage and flare the end of said tube.

2. A tube expanding and flaring tool having an opening therethrough and also having recesses communicating with said opening expanding rollers mounted in certain of said recesses and capable of contact by a mandrel extending through said opening, spherical flaring members mounted in the other recesses in said body and arranged alternately about the circumference of said body with respect to said rollers, said spherical members overlapping adjacent ends of the rollers, a split collar carried by the body and having a retaining flange for limiting the outward movement of said spherical members when contacted by said mandrel, and a ring encircling said collar to retain the sections thereof together.

In testimony whereof I have affixed my signature.

JAMES WALKER.
